UNITED STATES PATENT OFFICE.

THOMAS SHIPLEY, OF YORK, PENNSYLVANIA.

CONDENSER.

Application filed May 20, 1924. Serial No. 714,709.

To all whom it may concern:

Be it known that I, THOMAS SHIPLEY, a citizen of the United States, residing at York, in the county of York and State of Pennsylvania, have invented certain new and useful Improvements in Condensers, of which the following is a specification.

This invention relates to condensers of the shell and tube type, and particularly 10 to condensers for use in ammonia and other refrigerating systems.

In small refrigerating units there is a demand for a compact surface condenser that can be inexpensively constructed, and 15 that will meet the severe requirements of unattended service. The condenser must be absolutely tight against leakage and must remain so. It must be efficient, since these condensers are commonly cooled by city 20 service water and hence should operate with the minimum practicable water flow. It is important that the rate of water flow through the condenser unit shall be sufficiently rapid to prevent the deposit of scale 25 or sediment in the condenser.

From the standpoint of ease of construction and maintenance, the well-known water tube surface condenser is highly desirable. In this type of condenser the shell is provided 30 with tube sheets, near its ends, into which the ends of the tubes are expanded. The shell is provided with heads, beyond the tube sheets, forming water boxes.

In the simplest form of water tube condenser, the so-called single pass type, the water enters at one water box and discharges at the other, flowing through all the tubes in parallel. There are also multiple 35 pass types, in which baffles are placed in the different water boxes so that the water flows back and forth through various groups of tubes in parallel. This last construction is practicable in small condensers to produce 40 only a small number of passes.

A maximum water flow rate, and hence 45 a large number of passes, is highly desirable in the case of small ammonia condensers, and the construction forming the subject of the present application secures such flow 50 by connecting all the tubes in series with each other without requiring an unduly expensive or complicated construction. It can readily be modified, however, to produce the

flow through two or more sets of tubes in parallel, in the event that such an arrangement is desired.

Briefly stated, I make use of a shell and tube condenser having tube sheets and water boxes, preferably specially arranged to suit the requirements of the design. Within 55 the water boxes the end of one tube is connected with the open end of an adjacent tube by means of return bends having tapered ends or nipples which fit into the open ends of the tubes.

The joints between these return bends and the ends of the tubes can be made watertight, but when closed water boxes are used they need not be absolutely water-tight for the reason that when the water boxes are 60 flooded the pressures within and without the return bends are practically equalized. The leakage, if any, is consequently minimized, and whatever occurs has no harmful effect as it merely short-circuits in a very 65 small degree the tube affected by the leakage.

Where it is practicable to place the water inlet and outlet at opposite ends of the condenser, i. e. in different water boxes, it is 70 possible to flood the water boxes, for the purpose described, by connecting such inlet and outlet directly to respective water boxes and causing the water to flow from the inlet water box directly to the first tube and from 75 the last tube directly to the other water box, all other tube ends being connected together by return bends. It is convenient, however, to have the water inlet and outlet connections both at the same end of the 80 shell, and hence I prefer to use, and shall describe, an additional feature by which the water is led directly to the first tube and directly from the last tube. This permits 85 both connections to be made at one end. In 90 such case one return bend fitting is omitted from each water box, so that the water boxes are flooded and serve each to connect 95 two water tubes with each other.

The preferred embodiment of the invention is illustrated in the accompanying drawing in which:

Fig. 1 is a side elevation of the condenser partly broken away to show the internal construction;

Fig. 2 is a section on the line 2-2 of

Fig. 1, looking in the direction of the arrows;

Fig. 3 is a section on the line 3—3 of Fig. 1, looking in the direction of the arrows;

Fig. 4 is an end elevation of the condenser looking to the left relatively to Fig. 1;

Fig. 5 is an enlarged section through a tube sheet and the ends of a pair of tubes showing them connected by a return bend;

Fig. 6 is a fragmentary longitudinal section through the shell, head, and tube sheet, showing the means used to connect one end 15 tube of the series of tubes directly with a water connection, in this case the outlet connection.

The shell of the condenser is indicated at 11, and is provided at its opposite ends with 20 flanged tube sheets 12. The flanges of the tube sheets 12 are welded to the shell 11 producing practically an integral structure. The tubes 13 extend between the tube sheets

12. Each tube is expanded into a hole in 25 the tube sheet 12 and this hole is provided with a circumferential groove 14 into which the metal of the tube is pressed by the expanding tool so that a peculiarly tight joint is produced and so that the tubes have a 30 good staying action on the tube sheets.

The flanges of the tube sheets 12 project outward, as shown, and form the water boxes at the ends of the condenser shell 11. 35 These water boxes are closed by heads 15 and 16, each of which seats against a corresponding gasket 17. The gaskets 17 bear partly on the end of the shell 11 and partly on the flange of the corresponding tube sheet 12. The heads 15 and 16 are held in place 40 by cap nuts 18 which are threaded on the ends of tie rods 19. The tie rods 19 extend the entire length of the condenser and make tight joints with the tube sheets 12. They 45 serve as stays both for the tube sheets and for the heads.

The refrigerant vapor or gas to be condensed is introduced through the connection 20, and the condensed or liquid refrigerant is 50 withdrawn through the connection 21 which, as will be observed, is located above the bottom of the condenser. The purpose in so locating this outlet is to permit the condenser to serve also as a gravity oil separator. The oil is withdrawn through the 55 oil connection 22 at the bottom of the shell.

The inlet water connection is shown at 23 and the outlet water connection at 24. 60 These are identical in construction and can best be described with reference to Fig. 6, which shows the outlet water connection. The connector proper is of ordinary flanged form and is clamped in place by studs and nuts 33. It is provided with a threaded 65 opening to receive the water pipe 25. The fitting 24 fits in a recess formed in the head

16 and seats against the flanged end 26 of a tubular thimble 27 whose opposite end fits snugly into a tube 13.

In the case of Fig. 6, this tube 13 is the last tube of the series. It is not necessary 70 that an absolutely tight joint be made between the thimble 27 and the tube 13, but it is a simple matter to make a practically water-tight joint since the pressures on opposite sides of the joint are substantially 75 equal.

The various tubes 13 in the condenser are connected up in series by return bend fittings 28 having tapered nipples 29 at their ends, which fit snugly in the ends of adjacent tubes 13. The joints thus produced need not be absolutely tight, for the reason stated. Flooding of the water boxes is conveniently secured by omitting one return bend 28 from each water box, so that the 85 water box is in direct communication with two tubes 13, between which it serves as the connection.

The path of the water through the tubes can be traced on Figs. 2 and 3. The water 90 entering through the nipple 27 at the bottom of Fig. 3 makes three passes in the sixth or lowest tier, and two passes in the fifth or next lowest tier, at the end of which it discharges into the left-hand water box. 95 From the left-hand water box it flows via the right-hand tube in the third tier of Fig. 2. This tube is the left-hand tube in the third tier of Fig. 3 and as shown in that figure discharges into the right-hand water 100 box. From this box the water enters the fourth tier (via the left-hand tube in the fourth tier, Fig. 3), and makes five passes in the fourth tier, then four passes in the third tier, two passes in the second tier, three 105 passes in the first or top tier and thence discharges through the top thimble 27 and outlet connection 24.

Each of the heads 15 and 16 is provided with a corresponding projection 30 and 31, 110 so formed and positioned as to clear the return bends 28 only when these are properly placed, and only when the heads are presented properly. This precludes improper assembly of the device. These projections serve as a sort of template to assure correct positioning of the return bends, and while I prefer to construct these integrally with the head, it is obvious that this is not essential.

If all the tubes in the series be connected by return bends, and if care to be taken to secure tight joints with all the tubes, including also the inlet and outlet connections, then it is unnecessary to flood the water boxes, and these become functionless. In such case, the heads 15 and 16 may be omitted. The invention therefore permits the construction of a simple water tube condenser devoid of water boxes and making 120

use of water tubes expanded into tube sheets.

While I prefer the construction in which flooded water boxes are used as the more reliable, I do not limit my broader claims to this feature, but claim broadly the use of return bends having plug fits with adjacent tubes of a shell and tube condenser.

Water is the cooling medium usually used and hence it is common in this art to refer 10 to the cooling medium as "water", and to "water boxes", "water tubes", etc. In using such terms in my specification and claims, I merely adopt the terminology of the art for convenience, but imply no necessary limitation to water, since any suitable 15 fluid medium may be used.

What is claimed is:

1. The combination with a condenser of the water tube type including a pair of 20 spaced tube sheets, in which open-ended water tubes are fixed, and water boxes beyond the tube sheets; of removable tubular connectors mounted in the water boxes and having their ends frictionally retained in 25 the open ends of the water tubes to connect certain of said tubes in series.

2. The combination with a condenser of the water tube type including a pair of 30 spaced tube sheets, open-ended water tubes fixed in said tube sheets, and water boxes beyond said tube sheets; of a plurality of return bend connectors having tapered ends making plug fits in the ends of said tubes, said return bends being within said water 35 boxes, and being arranged to connect various of said water tubes in series.

3. In a condenser, the combination of a shell having tube sheets spaced from its ends to form water boxes; a plurality of water 40 tubes extending between and fixed in said tube sheets; and U-shaped connectors hav-

ing taper plug ends mounted in said water boxes with said ends frictionally retained in different tubes to connect the same with each other, said connectors being so arranged that, together with the water boxes, they connect all said tubes in series with each other, the connectors being surrounded by water in the water boxes whereby water pressures, internal and external to the connectors, are approximately equalized.

4. The combination with a condenser of the water tube type including a pair of spaced tube sheets, in which open-ended water tubes are fixed, and water boxes beyond the tube sheets; of removable tubular connectors in the water boxes and inserted into the open ends of the water tubes to connect certain of said tubes in series; removable heads for the water boxes; and means removable with said heads and having portions projecting into the spaces between said tubular connectors when the device is assembled, said projecting portions being so arranged as to preclude improper assembly.

5. In a condenser, the combination of a shell, tube sheets mounted in the ends of said shell and having outward projecting flanges which define water boxes beyond said tube sheets; removable covers closing the ends of said water boxes; open ended tubes connected at their ends with said tube sheets; and a plurality of U-shaped connectors inserted into and frictionally retained in the ends of some but not all of said tubes, in such manner that a plurality of tubes is connected with the water boxes and in series with each other.

In testimony whereof I have signed my name to this specification.

THOMAS SHIPLEY.
